UNITED STATES PATENT OFFICE.

DANA E. HARDING, OF ARLINGTON, MASSACHUSETTS, ASSIGNOR TO WRIGHT-HARDING COMPANY, OF EAST BOSTON, MASSACHUSETTS, A CORPORATION OF MASSACHUSETTS.

GLAZING MACHINE.

Application filed May 13, 1925. Serial No. 30,032.

The present invention relates to leather working machines, and more particularly to an improved machine for glazing or burnishing the surface of leather.

5 In the manufacture of leather, and particularly in the manufacture of leather adapted for use in the manufacture of uppers for shoes, an important and necessary step in the process of certain kinds thereof is 10 the production of a glazed or burnished surface on the hair side of the leather. This glazing or burnishing operation is, at the present time, uneconomically performed by machines wherein a rubbing stone is reciprocated on an anvil, the leather, whose surface is to be glazed or burnished, being placed 15 on such anvil and the operator, between the strokes of the rapidly reciprocating glass, shifts the position of the hide or skin on the 20 anvil in order to bring an unburnished or unglazed portion thereof into position to be operated on by the burnishing glass. The machines employed are crude and are extremely dangerous. It is necessary for the 25 operator to sit beside the machine and the reciprocating arm, to which is attached the burnishing stone, is moved rapidly to and fro. Numerous accidents have been caused, and are caused, on the slightest miscalculation 30 on the distance between the operator and the reciprocating arm. Various attempts have been made to reduce the hazard to life and limb, but because of the character of the machine and the function it must 35 necessarily perform, no successful glazing machine has been designed, at least up to the time applicant entered the field.

I have found that the glazing or burnishing operation is more readily performed and 40 a higher degree of polish or glaze imparted to the leather if the burnishing or glazing tool can be heated. With prior types of apparatus, this has been impossible, both because of the character of the glazing stone or glass and because of the fact 45 that it is necessary to reciprocate the the same at high speed. In my present invention I have obviated the objections noted as being inherent in prior apparatus and have designed a machine in 50 which reciprocating parts are entirely eliminated, in which the glazing or burnishing iron is heated to as high a degree as is necessary, and in which all danger to the operator is avoided. In carrying out my

present invention I utilize a corrugated cylinder, preferably of burnished metal, apply heat to maintain such corrugated cylinder at the desired temperature, and so mount 55 said cylinder as to have the same rapidly rotated. In conjunction with this cylinder, I arrange a feeding cylinder which is associated with, and rotates in, the same direction as the burnishing cylinder and at a greatly lower speed. I arrange the mounting for the feeding cylinder in such manner 60 as to have the feeding cylinder movable toward and from the corrugated cylinder and the degree of movement is made adjustable 65 so that the pressure exerted on the leather by the interaction of the feeding and corrugated cylinders may be regulated as desired. It is understood, of course, that the axes of the corrugated cylinder and the 70 feeding cylinder are parallel to each other. 75

The principal object of my invention, therefore, is an improved glazing machine.

Another object of my invention is an improved rotary glazing machine.

A further object of my invention is an 80 improved glazing cylinder for glazing machines.

Other objects and novel features of the construction and arrangement of parts comprising my invention will appear as the 85 description of the invention progresses.

In the accompanying drawing illustrating 90 the preferred embodiment of my invention,

Fig. 1 is a side elevation;

Fig. 2 is a front elevation, and

Fig. 3 is a fragmentary central sectional 95 side elevation.

Referring to the drawings, 10 designates a frame or base comprised essentially of side frame members 11 spaced apart from each other and held in position by cross bars 12. Secured to the upper rear ends of the side frame members 11 by bolts 13 are brackets 14 (but one of which is shown) and secured to the top faces of such brackets 14 are bearings 15 (but one of which is shown), and rotatably mounted in these brackets 15 is a shaft 16. Secured to the shaft 16 is a pulley 17 over which passes a belt 18 leading from any suitable source of power and through which power is transmitted to the mechanism to be hereinafter described. Secured to one end of the shaft 16, as clearly seen in Fig. 1, is a pulley 19. The lower rear ends of the side frame mem- 100 105 110

bers 11 extend rearwardly, as indicated at 20, and on such rearward extensions are secured bearing blocks 21, and rotatably mounted in the bearing blocks 21 is a shaft 22, this shaft being parallel to the shaft 16 above described. Keyed to the shaft 22 is a pulley 23, this pulley being in alignment with the pulley 19 above described as being secured to the shaft 16, and over these pulleys runs a belt 24 and by means of which power is transmitted from the shaft 16 to the shaft 22. The pulley 19 is smaller than the pulley 23 and, therefore, the shaft 22 will be rotated at a slower speed than the shaft 16. At the lower front end of the side frame members 11 are formed suitable bearings in alignment with each other and in the bearings is rotatably mounted a shaft 25, this shaft being parallel to the shaft 22. Secured to the one end of the shaft 25 is a pulley 26 which is in alignment with a pulley 27 secured to the upper end of the shaft 22. Over the pulleys 26 and 27 runs a belt 28 which, it will be noted by reference to Fig. 1, is crossed so that the direction of rotation of the shaft 25 is the reverse of the direction of rotation of the shaft 22, the respective directions of the rotation of the shafts 22 and 25 being indicated by arrows on Fig. 1. At the upper forward end of the side frame members is formed a cut out portion 29 substantially U-shaped in outline. The upper outer edge of the cut out portion 29 of each of the side frame members 11 has secured thereto on its under face bearings 30 in which is rotatably mounted a shaft 31, this shaft 31 lying parallel to the shaft 16. Adjacent to the inner faces of the side frame members 11 and secured to the shaft 31 are pulleys 32. Secured to the shaft 16 and in alignment with the pulleys 32 are pulleys 33. Over the pulleys 32 and 33 run belts 34 and by means of which power is transmitted from the shaft 16 to the shaft 31, the direction of rotation of such shaft 31 being indicated by the arrow in Fig. 1. Between the pulleys 32 and secured to the shaft 31 is a hollow cylindrical member 35, this member being of any desired diameter and length, and, by reference to Fig. 3, it will be noted that such cylindrical member 35 may be, as above described, hollow or may be solid, such feature, however, not being of particular importance. If made hollow, I may desire to place within the same means for heating consisting of an electrical heating device or gas heating device or any other suitable means. I prefer, however, in this embodiment of my invention, to place parallel with the axis 31 of the cylinder 35 a gas heating element 37 and attach such gas heating element to a source of fuel supply through a pipe 38, a controlling valve 39 being placed in such pipe 38 to control the flow of fluid. Secured to the front of the

side frame members 11 by bolts 40 are brackets 41 and secured to such brackets is a curved plate 42 which partially encloses the cylindrical member 35 and acts to retain the heat generated by the heating device 37 so that the cylinder 35 is surrounded by the envelope of heated air.

Secured to the side frame members in a position immediately below the bearings 30 are vertically arranged guides 43, such guides being spaced apart from each other to form parallel guideways. Slidably mounted in each pair of guides 43 is a bearing 44 and in the bearings 44 is rotatably mounted a shaft 45. Secured to one end of the shaft 45 is a pulley 46 which is in alignment with a pulley 47 secured to the shaft 25. Over the pulleys 46 and 47 runs a belt 48 and by means of which power is transmitted from the shaft 25 to the shaft 45. Secured to the shaft 45 between the side frame members 11 is a cylinder 49 of any suitable diameter and of approximately the same length as the cylindrical member 36. Preferably the cylindrical member 49 is covered with a layer 50 of resilient material such as rubber. Pivotally mounted on the shaft 45 and extending downwardly therefrom is a member 51 provided intermediate its ends with a cross bar 52. Secured to, and extending between, the side frame members 11 adjacent to the front bottom portion thereof is a shaft 53 on which is mounted a treadle member 54. One portion of the treadle member 54 extends upwardly and is pivotally attached at its upper end to a shaft 55 secured to the lower end of the member 51, as clearly shown in Fig. 2. Extending between the side frame members 11 and secured thereto by bolts 56 is a cross plate 57, such cross plate lying in front of the cross bar 52 above referred to. Adjustably secured to the cross bar 57 by nuts 58 is a rearwardly extending bolt 59, this bolt passing through a perforation 60 in the cross bar 52. A nut 61 threaded on the extreme rear end of the bolt 59 prevents the cross bar 52 from passing entirely off the bolt. Between the front face of the cross bar 52 and the rear face of the cross bar 57 is a coil spring 62 which tends to move the lower end of the frame 51 rearward about the shaft 55. Rotation of the treadle member 54 about the shaft 53 and in the direction of the arrow shown in Fig. 1, for example, will cause a forward movement of the lower end of the frame 51, and the upper end of the treadle 54 and the frame 51 act as a toggle, and the bearings 49 move upwardly, carrying the feeding cylinder therewith and brings the feeding cylinder into close association with the corrugated cylinder 35. By properly proportioning the frame 51 and treadle member 54, the degree of pressure exerted between the rotating cylinders 49 and 35 may be any desired. Secured to the

side frame members by bolts 63 is an angle member 64. Secured to the front faces of the side frame members 11 by bolts 67 are brackets 66. The upper faces of the angle members 64 and brackets 66 lie in the same horizontal plane, and secured to such upper surfaces in any convenient manner, as by bolts 67, is a worktable 68, such worktable being cut away, as indicated at 69, to allow 5 the feeding cylinder 49 to extend therethrough, as clearly shown in Fig. 3. In this Fig. 3 is shown a hide or skin 70 being fed through the cylinders 49 and 35 or in the direction of the arrow shown in such figure, 10 it being assumed that the cylinders referred to are rotating in the direction of the arrows shown.

The member 42 not only acts as a heat retaining shield for the cylinder 35, but also 20 acts as a guard to prevent possible injury to the workman by reason of coming in contact with the rapidly rotating corrugated cylinder 35 and the relatively slowly rotating cylinder 49. The distance between the lower edge of the shield 42 and the upper face 25 of the worktable 68 or the hide or skin 70 is so small that it is impossible for a workman to put his hands into position to be injured.

The operation of the device is as follows, it 30 being assumed that the various elements have been constructed and assembled as above described. Power being turned into the shaft 16 through the belt 18 and the feeding roll 49 and the corrugated roll 35 rotating in the direction of the arrow shown in the drawings, the heating device 37 is placed in action and the corrugated roll 30 gradually becomes heated. When at the 35 proper degree of heat, the operator takes a hide or skin, as 70, places the same on a worktable 68 and allows the same to be fed into position between the rollers 35 and 49. It is found that the hide or skin can be readily retained in any position in which it may 40 be placed without undue effort on the part of the operator, therefore, when the hide or skin is properly positioned, the operator, by 45 stepping on the treadle 54, moves the bear-

ings 44 upwardly and bringing the resilient surface 50 of the feed roll 49 into engagement with the under surface of the hide or skin 70 and forces the upper surface thereof into close association with the rapidly rotating corrugated roll 35. By properly manipulating the hide or skin 70, every portion of the surface thereof is brought into the burnishing and glazing action of the heated corrugated roll 35, after which pressure on the treadle may be released and the hide either withdrawn or, should it be deemed advisable, such hide or skin may be fed over the rear end of the worktable 68 onto any desired conveying apparatus that it may be desired to associate with the device.

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:

1. In an improved glazing and burnishing machine, the combination of a rotatably mounted corrugated and heated glazing and burnishing roll, a rotatably mounted feeding roll, means for rotating said rolls in opposite directions and at different rates of speed, and means for moving said rolls into and out of engagement with each other.

2. In an improved glazing and burnishing machine, the combination of a rotatably mounted heated glazing roll provided with a plurality of parallelly arranged corrugations on its periphery, means for rotating the same at a high speed, a shaft, slidably mounted bearings for said shaft, a feeding roll mounted on said shaft, a treadle, and connecting means between the treadle and said shaft for moving the same vertically to bring the feeding roll into and out of engagement with the corrugated roll.

In testimony whereof, I have signed my name to this specification.

DANA E. HARDING.
